UMBRELLA AND METHOD OF MANUFACTURING THE SAME

Herman Eichenbaum, Rockville Centre, N. Y.

Application January 3, 1952, Serial No. 264,763

4 Claims. (Cl. 135—33)

1

This invention relates to the manufacture of umbrellas and, more particularly, to an improved covering for the umbrella framework whereby the framework may be more easily assembled with the covering and much more securely attached to the covering.

The framework of an umbrella includes a carrying stick or handle having a crown secured adjacent its upper or outer end. Ribs are pivotally secured to this crown to extend radially therefrom and each rib has a brace or arm pivotally connected thereto intermediate its ends. The inner ends of the braces are connected to a sleeve or ring member slidably telescoped with the stick. Movement of this member along the stick serves to extend or collapse the ribs, spring catches or the like being provided to latch the member in the "open" and "closed" positions of the framework.

The covering comprises a series of generally sector shaped fabric panels joined in edge to edge relation to form a dome shaped covering. Each panel occupies the space between two adjacent ribs, and the joined edges of adjacent panels are anchored at their outer end to the outer end of the rib, a suitable protective tip being generally provided on the rib outer end. Inwardly of such securement, one or more transverse tack stitches secure the seam to the rib at spaced points along the latter.

In the case of folding umbrellas, the stick is generally in two telescoped sections and the ribs are jointed intermediate their ends. However, the covering is secured to the framework in the same manner as with non-folding umbrellas.

The present method of forming the covering and securing it to the framework not only presents difficulties in the assembly of the umbrella covering to the framework but also provides an insufficient securement of the covering to the framework. In turn, this not only increases the assembly cost but also shortens the useful life of the umbrella.

In accordance with the present invention, these difficulties are avoided and an improved construction provided by so securing adjacent panel edges together as to form a sleeve extending throughout at least the outer portion of the joined edges. This sleeve is formed with a closed outer end and an opening intermediate the ends of the joined edges. Thereby, the framework is assembled with the covering by simply inserting the ribs into the sleeves, thus providing a secure long-lasting attachment of the covering to the framework.

2

Preferably, the edges of adjacent panels are arranged in juxtaposed aligned relation, an elongated binder is folded over the edges, and the binder and edges stitched together to form the sleeve. A second binder is then stitched around the periphery of the covering, to reinforce the same and to close the ends of all the sleeves. Each sleeve is then transversely slit at a point between the ends of the edges to provide the openings for insertion of the ribs. Tack stitches may be used, if desired, to secure the exposed rib portions to the joined panel edges.

For an understanding of the invention principles, reference is made to the following description of a typical embodiment thereof as illustrated in the accompanying drawing. In the drawing:

Fig. 1 is a plan view of the covering for a folding umbrella as constructed in accordance with the present invention;

Fig. 2 is a section on the line 2—2 of Fig. 1;

Fig. 3 is a broken perspective view of a portion of a joined pair of panels, illustrating assembly details;

Fig. 4 is a detail partial plan view of the cover and framework as assembled;

Fig. 5 is a plan view of the covering as assembled to the frame of a folding umbrella;

Fig. 6 is a section on the line 6—6 of Fig. 5; and

Fig. 7 is an elevation view illustrating a detail.

In the drawing, the invention is illustrated as applied to a folding umbrella, to which the invention is particularly applicable. However, the principles of the invention are applicable equally to non-folding umbrellas.

Referring to Figs. 1, 2 and 3, the umbrella covering 10 is illustrated as comprising a plurality of generally sector-shaped panels 11 having their radial edges 12, 12 joined to provide the somewhat dome-shaped covering. In assembling the panels 11 to each other, edges 12, 12 are arranged in aligned juxtaposed relation, as best seen in Figs. 2 and 3. An elongated binder 15 is then folded over edges 12, 12, preferably with its edges 16, 16 turned for reinforcement. A longitudinal stitched seam 13 is then formed to join the edges 12, 12 and binder 15.

It will be noted that seam 13 is adjacent the inner longitudinal margins of binder 15 and inwardly of the edges 12, 12. Thus, the binder 15 forms a sleeve extending along the joined panel edges. A further binder 14 is then stitched around the periphery of covering 10 (Figs. 1 and 3), clos-

ing the outer ends of the sleeves 15. Sleeves or binders 15 are then transversely slit at points 17 intermediate the ends of the joined panel edges. The covering 10 is illustrated, in Figs. 4 through 7, as applied to a folding umbrella framework. This framework comprises a stick 20, which may be a pair of telescoped members, having a crown 21 on its upper or outer end. Rib sections 22 are pivotally connected to crown 21 to extend radially therefrom. Intermediate the ends of each rib section 22, an arm or brace 23 is pivotally connected, the inner ends of arms 23 being pivotally connected to a ring or sleeve member 24, movable along stick 20 to open and close the framework.

A connector 26 is secured to the outer end of each rib section 22, and has pivotally connected thereto an outer rib section 27. Thus, each rib comprises pivotally interconnected sections 22 and 27 foldable upon each other to form a compact bundle of the umbrella in the closed position. In the particular construction illustrated, the outer sections 27 are foldable outwardly, but the invention is equally applicable to folding frameworks in which the outer rib sections fold inwardly.

To assemble the covering 10 to the framework, each outer rib section 27 is slipped into a sleeve 15 through opening 17. Tack stitches may be used, if desired, to secure inner sections 22 to the joined panel edges. The outer ends of sleeves 15, closed by binder 14, limit outward movement of the ribs. The outer rib sections may, if desired, have rounded tips or ends thereon.

Due to an elongated engagement between the rib sections 27 and sleeves 15, a sturdy, long lasting connection of the frame to the covering is provided. Assembly is quick and relatively inexpensive. It should be noted that openings 17 are so located as to be adjacent the hinges 18 in the ribs when the umbrella is assembled.

While a specific embodiment of the invention has been shown and described in detail to illustrate the application of the invention principles, it will be understood that the invention may be otherwise embodied without departing from such principles.

What is claimed is:

1. In an umbrella of the type including a covered collapsible framework of ribs, a covering comprising a plurality of panels secured together in edge to edge relation, each pair of adjacent panel edges being in aligned juxtaposed relation, an elongated binder folded over and extending along each pair of juxtaposed edges, and stitching securing the binder and edges together to form a sleeve extending along at least the outer portion of the joined edges and closing the outer end of the sleeve, each sleeve having an opening therein intermediate the inner and outer ends of the joined edges to provide for insertion of a rib into the sleeve.

2. In an umbrella of the type including a covered collapsible framework of ribs, a covering comprising a plurality of panels secured together in edge to edge relation, each pair of adjacent panel edges being in aligned juxtaposed relation, an elongated binder folded over and extending along each pair of juxtaposed edges, and stitching securing the binder and edges together to form a sleeve extending along at least the outer portion of the joined edges, a binder stitched around the periphery of the covering formed by the thus joined panels to close the outer ends of the sleeves, each sleeve having an opening therein intermediate the inner and outer ends of the joined edges to provide for insertion of a rib into the sleeve.

3. In an umbrella of the type including a covered collapsible framework of ribs, a covering comprising a plurality of panels secured together in edge to edge relation, each pair of adjacent panel edges being in aligned juxtaposed relation, an elongated binder folded over and extending along each pair of juxtaposed edges, and stitching securing the binder and edges together to form a sleeve extending along at least the outer portion of the joined edges, a binder stitched around the periphery of the covering formed by the thus joined panels to close the outer ends of the sleeves, a transverse slit in each such first-named binder intermediate the inner and outer ends of the joined edges to provide for insertion of a rib into the sleeve.

4. In an umbrella of the type including a covered collapsible framework of ribs, each including a pair of pivotally interconnected sections, a covering comprising a plurality of panels secured together in edge to edge relation, each pair of adjacent panel edges being in aligned juxtaposed relation, an elongated binder folded over and extending along each pair of juxtaposed edges, stitching securing the binder and edges together to form a sleeve extending along at least the outer portion of the joined edges, a binder stitched around the periphery of the covering formed by the thus joined panels to close the outer ends of the sleeves, a transverse slit in each such first-named binder intermediate the inner and outer ends of the joined edges at a point corresponding to the pivotal interconnection of the rib sections to provide for insertion of an outer rib section into the sleeve.

HERMAN EICHENBAUM.
